UNITED STATES PATENT OFFICE.

JACOB F. FRITTS, OF FORTY FORT BOROUGH, PENNSYLVANIA, ASSIGNOR TO WALES ADDING MACHINE COMPANY, OF WILKES-BARRE, PENNSYLVANIA, A CORPORATION OF PENNSYLVANIA.

CALCULATING-MACHINE.

1,333,167.

Specification of Letters Patent.

Patented Mar. 9, 1920.

Application filed July 15, 1918. Serial No. 244,970.

To all whom it may concern:

Be it known that I, JACOB F. FRITTS, a citizen of the United States, residing in the borough of Forty Fort, State of Pennsylvania, have invented new and useful Improvements in Calculating-Machines, of which the following is a specification.

My invention relates to calculating machines, of the type disclosed in the well known Wales machine, and is more particularly directed to the control of an accumulating mechanism having the general characteristics of that shown in U. S. patents to Wales 797,032, August 15, 1905, and McFarland 842,232, January 29, 1907.

In machines built in accordance with the above named patents, the counters remain disengaged from their drive members, in adding operations, until the drive members have advanced a number of steps sufficient to register on the counters, the amount set up on the keyboard, after which the counters engage their drive members, and the latter are then retired to effect such registration. Counter-disengaging means is actuated at the completion of the adding operation, to disconnect the counters from their drive members, and to normally hold the counters in disengaged position. The counter-disengaging means is displaced at the beginning of the adding operation, and counter-detaining means then becomes effective, to delay the engagement of the counters and their drive members until the latter have completed their advance.

In the particular constructions shown in the above mentioned patents, the means which delays the engagement of the counters with their drive members after the displacement of the counter-disengaging mechanism, until the drive members have completed their advance, includes legs or counter supports depending from opposite ends of the counter axle, and when the machine is idle, the feet of these supports lie slightly above and in alinement with steps or rests rigidly mounted in the side frames.

Upon the forward stroke of the main drive shaft, the counter-disengaging props are displaced, and the racks or drive members advance. The displacement of the counter-disengaging props allows the coun-

ters to descend slightly from their normal disengaged positions until the feet of the counter supports contact the steps.

In this intermediate position, the counters still remain out of engagement with their racks or drive members until, near the end of the forward stroke of the main drive shaft, the counter-disengaging means, a part of which, during such forward stroke, traverses slots in links connected to the counter supports, finally reaches the end walls of such slots and unseats or trips the counter supports from their steps, to effect the engagement of the counters with their drive members.

The slight preliminary descent of the counters actually amounts to a few thousandths of an inch, and is desirable on machines like those shown in the patents referred to, in order to provide a safety clearance between the stationary step and the foot when the counters are being disengaged from their racks, to insure the escape of the foot past the edge of the step and its subsequent alinement with the step. Such clearance also compensates for the commercially unavoidable play in the connections between the main drive shaft and the counter-disengaging means, as well as for other slight inaccuracies in assembling, and varies in different machines.

The main drive shaft on its return stroke, retires the adding racks or drive members which, during such retirement, register the amount on the counters. Near the end of the return stroke, and immediately after the retirement of the racks, the counter-disengaging means becomes effective to disconnect the counters from their drive members in readiness for a succeeding operation.

It is obvious that the disengagement of the counters from their drive members immediately after the drive members have imparted rotation thereto, is liable to permit further rotation of the counters, due to momentum, especially in rapid operations of the machine.

To prevent such overrotation, the drive members of the former machines, as they arrive in normal retired position, operate overrotation preventing pawls which lock the counters against turning independently

of the racks, except when a carry is to be effected. The overrotation pawls are automatically retracted to idle positions upon the advance of the drive members, to free the counters for rotation.

The machine herein shown, however, while basically similar in operation to the machine shown in the patents heretofore referred to, is simplified in construction, in many ways.

Thus, segmental racks traveling in a fixed arc are substituted for the longitudinally reciprocating racks of the former machines, and longitudinally shiftable combined counter locking members and carrying bars located above the counters, and with which the counters normally engage, replace the former style of carry, which embodied a rocker journaled intermediate its ends and having a carrying dog on one end, and the overrotation preventing pawl on the other end.

In the present machine, the counters travel up and down between the segments and the carrying bars.

Obviously, when the counters are in mesh with their drive members, they must be out of mesh with the combined counter locking members and carrying bars, and vice versa, when in mesh with their counter locking members, they must be out of mesh with the drive members.

Furthermore, in order to reduce to a minimum, the possibility of accidental or uncontrolled rotation of the counters, the distance between the racks and counter locking members is so reduced, that the counters are never entirely disconnected with one set of control members before they have begun to engage the other set.

In view of this compact arrangement of counters, drive members and counter locking members, the preliminary drop formerly permissible in machines constructed in accordance with the patents mentioned, cannot now be allowed, because the counters would then engage both the locking members and the racks and lock the machine against operation.

Therefore, one object of this invention is the provision of counter-detaining means effective upon the displacement of the counter-disengaging means, to hold the counters in their normal idle position, disconnected from their drive members until the latter have completed their advance.

As a consequence, the counter-detaining means maintains a fixed and proper mesh between the counters, and their combined carry and counter locking bars, when the counters are disengaged from their adding racks, whereby to render the transfer action of the combined carry and counter locking bars accurate and positive.

In machines constructed in accordance with the present invention, the carrying operation is effected by the combined carrying and counter locking bars, each of which tends to advance, due to the tension of drive springs connected thereto, but is normally held in set or cocked position by detents tripped or controlled by the counters.

When, in a machine arranged to calculate in accordance with the decimal system, a counter of lower denomination is turned by its adding rack or drive member from its "9" to its "0" position, a cam or trip member on the counter displaces the detent to release the combined carrying and counter locking bar of the next higher denomination, to the action of its drive spring. Carry restraining and restoring means delays the operation of the released carrying bars until the counters are disconnected from their drive members and connected with their carrying bars, as above explained.

Since the longitudinal travel of the combined carrying and counter locking bars, in a transferring operation, must of necessity be fixed in order not only to positively turn their counters the full distance or step between two digits, but also to prevent an excessive rotation of the counters beyond such one step rotation, it is obvious that the amount of engagement between the counters and their carrying bars and detents must be held very nearly perfect, to prevent undue lost motion of the carrying bar relatively to its counter, which might render the machine inaccurate.

My invention, by enforcing and maintaining the proper degree of engagement between the counters and their carrying bars, throughout the period during which a carry can be effected, relieves the counter-disengaging and supporting means of this duty, and reduces the amount of play and looseness between the parts.

There is unavoidably, an intermediate point in the travel of the counters between their drive members and counter locking bars, at which the engagement of the counters with both sets of control devices is very loose, and at such point, if the counters were rotated under sufficient impetus, they might spring the teeth of their pinions past the teeth of the counter locking members and of the drive members, and thereby effect an incorrect registration.

The improved counter-detaining means herein set forth reduces such possibility to a minimum by preventing a preliminary partial descent of the counters, and by holding the counters in full mesh with their counter locking members until the drive members have completed their advance, whereupon the counter-detaining means is disabled to permit the instantaneous disen-

gagement of the counters from their locking members and their engagement with the drive members.

The counter-detaining means thus accurately maintains the clearance between the counters and their drive members throughout the entire advance of the latter.

In addition, novel means is employed to return the counter-detaining means to position to be effective upon the displacement of the counter-disengaging means.

To this end, the counter-detaining step is swiveled and means is employed to insure the rocking of the step by the counter-detaining support, as the support is tripped off the step, the step being rocked to a position to receive the support during the disengagement of the counters from their drive members, after the amount is registered; and when the support is re-seated on its step, it restores the step to normal position, and causes it to take up all space or lost motion between itself and the support, so as to prevent any premature partial disengagement of the counters and their combined carrying and locking members, prior to the disconnection of the support and its step on the next operation.

With the foregoing and other objects in view, my invention includes certain novel features and combinations of parts, all of which will be more fully explained herein-after and particularly pointed out in the claims.

In the accompanying drawings, Figure 1 is a side view of one embodiment of my invention, applied to the well known Wales type of machine, the handle being in its normal, idle position;

Fig. 2 is a detail sectional view, showing the counters in their normal idle positions engaged with the combined counter locking members and carrying bars. This view also shows the drive mechanism for the segmental racks;

Fig. 3 is a detail plan view of a counter-selecting means employed in machines having a plurality of sets of counters;

Fig. 4 is a detail side view of the same; Fig. 5 is an enlarged perspective detail of the shiftable rest or step on which the counter-detaining support seats;

Fig. 6 is a side view, like Fig. 1, but showing the positions of the parts when the main drive shaft has completed its forward stroke, at which time the counters are disengaged from their counter locking members and engaged with their drive members;

Fig. 7 is a side view, similar to Fig. 1, with the total or clearing key depressed;

Fig. 8 is an enlarged detail view of the counters and their opposed control members, showing one of the combined carrying and counter locking members associated with one set of counters, discharged, the

corresponding denominational carry and counter locking member for the remaining set of counters being in its normal cocked or set position; and

Fig. 9 is a detail perspective view of one of the detents for the carrying members.

The base 968 (Fig. 1) supports side frames 969^a, between which are arranged a keyboard or selective mechanism, (Fig. 2) the operation of which determines the value of the amount to be registered on the counters, and an accumulating mechanism, including one or more series or sets of counters, and drive members therefor, the advance of the latter being controlled, in adding operations, by the keyboard.

The keys 117 (Fig. 2) of the keyboard are arranged in denominational rows and control correspondingly arranged rows of stops 115 located in the paths of denominationally arranged positioning bars 310, to determine the values of the digits to be registered on the coacting sets of counters 490 or 490^a.

Front arms 312 conveniently journaled on a tube 300^b surrounding a cross shaft 300, 90 and mounted at its opposite ends in the side frames 969^b, pivotally support the forward ends of the longitudinally extending positioning bars 310, at points 351. Rear arms 311, journaled on a cross rod 301 extending 95 between the side frames, pivotally support the rear ends of the positioning bars at points 350.

Segmental racks or drive members 410, the stocks 410^m of which are journaled on a 100 cross shaft 401 located intermediate the cross rod 301 and the shaft 300, are pivotally connected with the positioning bars 310, by studs 450 entered in slots 310^m in their corresponding positioning bars 310. 105

The positioning bars have a substantially rectilinear forward and backward travel, whereas the drive members 310 travel an arcuate path.

Restoring links 312^b depending from forward extensions 312^m of the respective front supporting arms 312, are forked at their lower ends to embrace a transversely extending restraining and restoring bar 294 mounted in the forward ends of a pair of 115 levers 220 journaled at their rear ends on a fulcrum shaft 508^a extending across the machine.

Springs 383 connect the restoring links 312^a with a slotted guide plate 220^b fastened 120 to the restraining and restoring bar 294, and tend to rock the front supporting arms 312 forwardly to advance the positioning bars 310 against the key-set stops 115, or the rack detents 221 normally lying in the paths 125 of the several positioning bars. The rack detents are adapted to be struck by and shifted to idle position by the individual stops when set for operation. The forked ends of the restoring links 312^a are guided 130

in the slots in the guide plate 220^b to prevent displacement, all as more clearly illustrated and explained in the copending application of Pentecost & Fisher, Serial No. 5 245,273, filed July 17, 1918.

Suspension or radius bars 323 journaled at one end on the cross tube 300^b, carry rolls 340^a adapted to traverse cam slots 220^m formed in the levers 220 to vibrate the latter, and with them the restraining and restoring bar 294.

Draft links 214 connect the suspension bars 323 with cranks 212 fixed on a main drive shaft 200 journaled in the side frames 15 969^a. The main drive shaft may be stroked forwardly in any suitable manner, as by the handle 10^b, against the tension of a main restoring spring 285, which is adapted to restore the main drive shaft and connected 20 parts to, and retain them in, their home positions.

Normally the rolls 340^a of the suspension bars 323 lie at the rear ends of the cam slots 220^m in levers 220, to retain the restraining 25 and restoring bar 294 at one end of its travel, and hold the positioning bars 310 and the drive members 410 in their retired positions, against the tension of springs 383.

The denominational counters, of which 30 there may be one or more sets 490, 490^x, contact with and are turned by the drive members 410. Two similar sets of accumulators are shown in the accompanying drawings, and a description of one will suffice for both, it 35 being understood that my invention will operate exactly as well whether one or more sets of accumulators are employed. If but a single set is used, the counter-selecting mechanism hereinafter referred to, would be 40 unnecessary.

Each set of accumulators includes several counters loosely mounted for independent rotation on an axle 400 supported by a series of arms 414 fastened to a cross rod 404. 45 Pinions 435 associated with the respective counters, are adapted to mesh with their corresponding racks or drive members 410. The arms 414 project toward each other from the parallel rods 404 to hold the respective 50 sets of accumulators parallel with and closely adjacent each other, so that counters of like denomination lie in tandem.

Referring to Fig. 3 of the drawings, it will be seen that the axles 400 terminate 55 short of the left hand side frame 969^a and that the counters and axles are supported at such left hand end by arms 414^a fast on the left hand ends of the cross rods 404, and parallel with the arms 414, the arms 414^a carrying studs 458 (Figs. 3 and 4) which project 60 over and rest upon a vertically shiftable head 324 arranged parallel with and adjacent the left side frame 969^a.

The right hand ends of the counter axles 65 400 may be similarly sustained as far as the

present invention is concerned, and the supporting heads 324 are of sufficient length to lie beneath and afford rests for the sustaining studs 458 of all sets of counters.

The stems 324^m (Fig. 4) of the vertically shiftable plates 324 are slotted at their lower ends to embrace and be guided by a shaft 402 journaled in the side frames 969^a.

Studs 356 (Figs. 1, 3 and 4) project outwardly from the respective supporting plates 75 324 and through vertical guide slots 969^m (Figs. 1 and 6) in the upper edges of the opposite side frames. The outer ends of the studs pass through arms 322^m of bell cranks 322 pivoted at 952^a to the side frames, and 80 counter-disengaging means, including props 319 pivoted to the arms 322^m at 357, normally hold the arms 322^m in elevated position, with the pinions 435 disengaged from the racks or drive members 410 and engaged with the 85 combined carrying and counter locking bars or members 610, 610^a, as shown in Fig. 2.

The props 319 are slotted at their lower ends, at 319^m, (Fig. 1), to embrace and rest upon a trip rod 303 mounted in and connecting 90 the suspension or radius bars 323. The trip rod and suspension bars form a swinging frame oscillated by the draft links 214 actuated from the main drive shaft 200.

Depression of the keys 117 rocks their 95 levers 116 to project the corresponding stops 115 into the paths of the coacting positioning bars 310, and displace the denominational corresponding rack detents 221.

The main drive shaft 200 is now stroked 100 forwardly against the tension of the main restoring spring 285, to advance the draft links 214 and swing the suspension bars 323 toward the front. The rolls 340^a on the suspension bars 323 traverse the cam slots 105 220^m and rock the levers 220 downwardly. The levers 220 withdraw the restraining and restoring bar 294 to further tension the rack driving springs 383, which cause the restoring links 312^a to swing the arms 312 forwardly, the links 312^a following and being guided by the bar 294 and guide plate 220^b.

The arms 312 advance the positioning bars 310 together with the racks or drive members 410 connected thereto, until the projected stops 115 arrest the positioning bars. The rack detents 221 arrest the positioning bars in those denominations wherein no keys have been depressed, before such positioning bars have advanced past their zero position. 120 (See Fig. 2.)

The arrest of the positioning bars by the projected stops occurs prior to the completion of the forward stroke of the main drive shaft.

The rear ends of the cam slots 220^m conform to the arcuate travel of the rolls 340^a, to permit the suspension bars 323 (Figs. 1, 6 and 7) to advance the trip rod 303 prior to the advance of the positioning bars 310. 125 180

- The trip rod first travels in a descending arc to deprive the props 319 of support, and therefore, the counters would be lowered into mesh with the racks or drive members 5 410 before the latter have advanced toward the projected stops 115, were it not for the provision of a counter-supporting and detaining means, which includes the present invention, now to be explained.
- 10 Such counter-detaining means, comprises counter supports or legs 316 pivoted on and depending from the studs 356 of the supporting plates 324, on opposite sides of the machine. The lower free ends of the counter 15 supports or legs may conveniently terminate in feet 316^m adapted to rest on seats 958^a to maintain the counter-supporting plates 324 elevated and the counters themselves in their normal disengaged positions relatively to 20 the racks or drive members 410, and engaged with the counter-locking bars 610, 610^a, until the positioning bars 310 and drive members 410 have completed their advance, in adding operations.
- 25 This invention is particularly directed to the step or seat 958^a (Figs. 1, 5 and 6) one on each side frame, and each, in the present form illustrated, comprising a gudgeon 958^m journaled in the side frame, and terminating 30 at its outer end in the recessed step 958^a on which the foot 316^m rests. As shown, this step or seat is preferably angular, but it may be of other conformation suitable to effect the results hereinafter set forth.
- 35 The seat portion 958^a normally contacts the foot 316^m and projects in line with, the axis of rotation of the gudgeon 958^m.
- The back 958^r of the step extends upwardly from the seat portion and is normally contacted by the side of the leg 316, 40 a spring 384^a connected to the leg or counter support 316 operating to maintain the parts in such position, that the seat 958^a remains substantially horizontal to support 45 the counters against a premature partial disengagement from their detents, during the displacement of the counter-disengaging means, which includes the props 319 and trip rod 303.
- 50 The ends of the trip rod 303 enter slots 321^m in links 321 pivoted at 257 to the legs or counter supporting members 316, and the trip rod, during the first part of its forward stroke, idly traverses the slots 321^m in the 55 links 321 and shifts along the slots 319^m in the props 319, which latter are held suspended by the legs 316 and steps 958^a. The lengths of slots 321^m are so proportioned that the trip rod will contact the outer end 60 walls thereof, near the end of the forward stroke of the main drive shaft, thus allowing sufficient time for the advancement of the racks positioning bars 310 and 410. The trip rod 303 upon contact with the outer 65 walls of the slots 321^m, draws the links 321

forwardly and unseats the legs 316 from the steps 958^a, against the tensions of springs 384^a to thereby deprive the arms 322^m and plates 324 of support, whereupon the latter descend to effect the engagement of the 70 counters, or their pinions 435, with the drive members 410, preparatory to registering the amounts represented by the advanced drive members, on the counters.

Springs 380, which connect the props 319 75 with the trip rod 303, are tensioned by the latter on its advance, and augment the weight of the parts to instantaneously snap the counters out of engagement with the combined carrying and counter-locking 80 members 310, 610^a and into engagement with the drive members 410, as soon as the legs 316 are tripped off their steps. (See Fig. 6, and the left hand set of counters 490^x in Fig. 8)

85 As the legs slide off the outer edges of the seating faces 958^a of their steps, the weight of the counters and associated parts, assisted by the tension of the springs 380, operates to rock the steps forwardly until arrested by the contact of stop arms 922 secured to the steps, with abutments 960 on the side frames.

The stop arms 922 are formed of pliable metal to permit adjustment of the rocking 90 throw of the steps, by bending the stop arms toward or from the abutment.

The abutments 960 preferably arrest the steps prior to the complete disconnection of the legs 316 and steps, light springs 985^a 100 connected to projecting ears on the stop arms, operating to yieldably hold the steps in rocked position to receive the feet 316^m during the return of the parts to normal position, such springs, of course, assisting to rock the steps forwardly.

105 The legs 316 drop below the edges of the seating faces 958^a of the steps when finally unseated, (Fig. 6).

The main drive shaft 200, on its return 110 stroke, restores the trip rod 303 and the suspension bars 323 to normal position. The rolls 340^a of the bars 323, retrace the cam slots 220^m in levers 220 to raise the levers and press the restraining and restoring bar 115 294 against the lower ends of the advanced, forked restoring links 312^a. The restoring links in turn, rock the front arms 312 rearwardly to retire the positioning bars 310 and racks or drive members 410 to their normal positions, during which retirement, the advanced racks turn the counters to register thereon the amount represented by the depressed keys.

120 The trip rod 303 during the first part of its return stroke, idly traverses the slots 319^m in the props 319, and the slots 321^m in the links 321, to afford time for the racks, as they retire, to register amounts on the counters. The trip rod, as it approaches 125

130

the end of its return stroke, and after the racks have been completely retired, begins to swing upwardly, owing to the influence of the radius or suspension bars 323, and contacts the upper ends of the slots 319^m of the props 319 to force them upwardly and rock the arms 322^m, which in turn, raise the supporting plates 324 and disengage the counters 490 or 490^x from their racks or drive members 410.

10 The arms 322^m, as they rise, lift the legs 316 until the feet 316^m thereof clear the outer edges of the seating faces 958^p of the steps 958^a, which faces at this time are 15 downwardly inclined to receive the feet, whereupon the superior springs 384^a connected to the legs 316, snap the feet rearwardly against the backs 958^a of the seats, to cause the seats to swivel on their 20 gudgeons 958^m against the lighter tension of the springs 985^a, and take up any clearance between the seats and the feet, when the counters are in normal disengaged position relatively to the racks, and in complete 25 engagement with their combined carrying and counter locking bars 610.

Thus it will be seen that the steps 958^a and counter supports or legs 316, will support the counters in mesh with their counter 30 locking bars against a premature partial descent, after the counter-disengaging props 319 are displaced, until tripped by the counter-disengaging means after the racks have completed their advance in an adding 35 operation.

The rocking seat compensates for wide variations in the length of the legs, loose play, or distance between the racks 410 and counter locking members 610, 610^a in 40 different machines.

The projected stops 115 and the depressed keys 117 are released on the return stroke by means substantially like that disclosed in U. S. patents to Wales and to 45 McFarland first mentioned.

The combined carrying and counter locking bars 610, 610^a (Figs. 2 and 8) are arranged in pairs longitudinally of the machine, and are slidably supported for end- 50 wise travel on parallel cross rods 600 extending between the opposite side frames 969^a.

Springs 680 connected to the forward ends of the respective carrying and counter 55 locking bars 610, 610^a tend to advance the bars, which, however, are normally held in cocked or retracted position, shown in Figs. 2 and 8, by detents 612, journaled on the respective shafts 600 adjacent the front 60 and rear ends of the bars 610, 610^a, and having lateral lips 612^m adapted to lie in the paths of the corresponding shoulders 612^p formed near the forward ends of bars 610^a and near the rear ends of bars 610.

65 The forward ends of the combined carry-

ing and counter locking members 610, 610^a, are slotted, as at 610^m to embrace the front rod 600, the rear end walls of the slots operating to limit the advance of the members, when released by the detents 612.

70

As the counters 490 or 490^x turn in the direction of the arrows, Fig. 8, past their "9" positions, they press cams 411 turning with the respective counters, against ears 612^r projecting from the respective detents 612 into the circular paths of said cams, to displace the detents and release the carrying bars 610, 610^a to the action of their drive springs 680.

The rotation of the counters 490, 490^x 80 may take place while the counters are engaged either with their drive members 410, or with their combined carrying and counter locking bars 610, 610^a.

As each carrying operation must of necessity be initiated while the counters are in mesh with their drive members 410, it is obvious that to permit the released carrying members 610, 610^a to advance at such times, would be futile and effect no useful 85 result, as the counters are, at such period, out of engagement with the carrying members. On the other hand, if the carrying bars are retained in set or cocked positions, the cams 411, which have released the detents 612, will wipe past the detents and permit them to return to locking position under the influence of their springs 681.

Therefore, the carry resetting bar 613^m is arranged to arrest the advance of the 100 tripped carrying bars at such time, after the bars have displaced their shoulders 612^p relatively to the detents, to prevent the latter, when released by the cams 411, from becoming effective. This idea is well known 105 in the art and forms no part of the present invention.

As soon as the counters have disengaged from their drive members 410 and engaged their respective combined carrying and 110 counter-locking members 610, 610^a, the carry resetting bar is withdrawn to enable the tripped carrying members to complete their advance and turn their corresponding counters in transferring operations.

115

The rear end walls of the slots 610^m arrest the carrying members 610, 610^a after they have advanced a sufficient distance to turn their corresponding counters a single step in a carrying operation, and the determination or limitation of this carrying action is a very important feature in calculating machines, as a comparatively slight variation therein may form the underlying cause of an under or an over 125 carry.

120

In the present invention, the carrying members 610, 610^a, when in cocked or set position, locate their teeth 610^p in such relation to the pinions 435 of the counters, that 130

upon the engagement of the pinions with their carrying members, the former, together with their counters, are rolled very slightly backwardly.

5 Upon the engagement of the pinions 435 with their adding racks 410, the counters are rolled very slightly forwardly. This slight roll is hardly noticeable.

The preliminary advance permitted the 10 carrying members 610, 610^a positions the teeth 610^b thereof, so that the pinions 435 mesh directly therewith, without rolling, and thus when the carrying bars are free to advance until arrested by the front cross rod 600, their travel is sufficient to turn the 15 pinions 435, and consequently, the counters 490, 490^a, the required distance.

It will be plain, however, that the depth 20 of mesh of the teeth of the pinions 435 with the teeth 610^b of the carrying bars is an important factor, as excess play would necessarily have to be taken up by the carrying bars which, as heretofore explained, have but a fixed and limited advance. If such 25 excess play existed, the carrying bars would not be able, under all working conditions, to turn the counters the requisite step, and under such conditions, if the counter onto which a transfer is to be made, were standing at "9", (as shown in dotted lines at 30 the left in Fig. 8), the transferring operation might turn it only far enough to bring its cam 411 under the detent 612 controlling the carrying bar for the next higher 35 denomination, instead of to the full line position shown at the left in Fig. 8. As a result, the cam 411 would maintain the detent displaced, and prevent its return to effective position.

40 My adjustable counter support, prevents the occurrence of such disadvantages, by maintaining a constant depth of mesh between the teeth of the pinions 435 and the teeth of the carrying members 610, 610^a, and 45 consequently, controls the amount of play or looseness between the meshed teeth of the pinions and carrying members.

In clearing the counters of amounts accumulated thereon, the counters are disengaged from their combined carrying and counter locking members 610, 610^a, and engaged with their drive members 410 prior to the advance of the latter. This necessitates disabling the means which ordinarily 55 detains the counters out of mesh with their drive members after the displacement of the counter-disengaging props 319.

The engagement of the counters with their drive members prior to the advance of the 60 latter, enables the drive members to reversely rotate the counters until the latter are arrested by the contact of their cams 411 (Fig. 2) with the forward faces of the lips 612^c, at which time, the counters are each in their 65 zero positions.

Depression of either of keys 327 or 327^b (Figs. 6 and 7) rocks one arm 317^b of a set lever fastened to the cross shaft 300 to turn the latter, and with it, a corresponding set lever on the opposite side of the machine. 70 The remaining arm of the set lever, operates a slide member 320 to disable the rack detents 221, and to release any depressed numeral keys, which mechanism forms no part of the present invention, and is fully explained in U. S. patent to McFarland, 842,232, January 29, 1907.

Links 315 connect the set levers with the legs or counter supports 316, so that upon the depression of the keys 327 or 327^b, the 80 set levers are rocked to draw the links 315 forwardly and swing the counter supports 316 out of alinement with their steps 958^d prior to the displacement of the counter-disengaging props 319 (see Fig. 7). A latch 85 216^d takes over a stud 354^m on the set lever arm 317^b to retain the latter in adjusted position.

The counter-disengaging props 319 still hold the counters in elevated position, as 90 shown in Fig. 7, but the main drive shaft 200, upon starting its forward stroke, immediately lowers or displaces these props through the operation of the trip rod 303, to effect the engagement of the counters with 95 their drive members 410 before the latter advance.

The light springs 985^d rock the steps 958^d to receiving position, as the legs or counter supports swing out of alinement from the 100 steps, and the feet 316^m of the legs descend below the steps as the counters engage their drive members.

If the set levers 317^b are released to the action of their restoring springs 382, at 105 the end of the forward stroke of the main drive shaft, the counters disengage from their drive members and engage their carrying and locking members 610, 610^a at the beginning of the return stroke of the shaft, 110 through the action of the set levers 317^b, the thrust links 314, and the bell cranks 313 which contact studs 357^d on the legs 316 to lift the latter, all as fully explained in Patent No. 842,232, the counters being held 115 by this train of mechanism in their normal idle position until the counter-disengaging props restore to effective position near the end of the return stroke.

The action of the leg 316 and the shift- 120 able step 958^d under this operating condition is the same as previously set forth in explaining the adding operation.

The counter-selecting means to enable the operator to select either set of counters for 125 operation includes the rock shaft 402 (Fig. 4) journaled in the respective side frames, which rock shaft supports at its opposite ends, disabling members 418^a fixed to the shaft and projecting upwardly between the 130

counter axles 400. The members 418^a are of sufficient length so that when such members are in their intermediate positions, they extend beneath the projecting studs 458 of both series of counters when the latter are in their normal elevated positions, shown in Figs. 1, 2, and 4, to lock the counters out of engagement with their racks 410.

A handle or lever 418^a projects from one of the disabling members 418 to enable the operator to adjust the disabling members to their forward, rearward or intermediate positions, to lock out either one or both of the sets of counters 490, 490^a. By adjusting the disabling heads 418^a to one of their extreme positions, the heads are withdrawn from beneath the studs 458 on the sustaining arms 414^a associated with one set of counters and inserted beneath the studs 458 of the sustaining arms 414^a belonging to the other set of counters, to free the first named set for operation, and lock the last named set out of operation.

Opposed slots 418^a formed in the respective heads of the locking members 418 embrace the studs 458 of the set of counters which is to be held inoperative, the slots being arcuate to compensate for the circular travel of the plate, so as not to shift the counters from their normal disengaged positions.

Pawl 324^b pivotally mounted on oppositely projecting arms 324^b of the respective plates 324, and connected by springs 388, take over the studs 458 of that set of accumulators selected for operation, to lock such set fast to the sustaining plates against relative movement.

The pawls or latches 324^b contact the opposite edges of the heads 418^a interposed between the latches, so that when the heads are shifted to either of their extreme positions, they release one or the other of the sets of pawls 324^b for coöperation with the studs 458, and maintain the other pair of latches disabled.

Changes may be made in the form and arrangement of the several parts set forth without departing from the spirit and scope of this invention.

What I claim as new, is:—

1. In a calculating machine, the combination with a drive member; a counter adapted to engage with and disengage from the drive member; and means to normally hold the counter disengaged, said means adapted to be displaced to permit the engagement of the counter with its drive member; of separate mutually movable means to temporarily retain the counter in normal disengaged position, upon the displacement of the counter-disengaging means, in adding operations and means controlled by the counter-disengaging means to disable the

retaining means, to permit the engagement 65 of the counter with its drive member, and later, to reenable the retaining means as the counter disengages from its drive member.

2. In a calculating machine, the combination with a counter, and a drive member 70 relatively engageable and disengageable; counter-disengaging props and a trip rod to positively disengage the counter from the drive member and hold it in such disengaged position, said props adapted to be displaced 75 to enable the counter to engage its drive member; and means including shiftable steps to retain the counter in its normal disengaged position upon the displacement of the counter-disengaging props, in adding 80 operations, said trip rod adapted to disable the counter-retaining means at a predetermined period in the operation of the machine.

3. In a calculating machine, the combination with a counter; and a drive member 85 relatively to which the counter is adapted for engagement and disengagement; counter-disengaging means to positively disengage the counter from the drive member and hold 90 it in such disengaged position, said means adapted to be displaced to enable the counter to engage its drive member; and means to temporarily retain the counter in its normal disengaged position in an adding operation 95 upon the displacement of the counter-disengaging means, including a support connected with the counter; and a shiftable step normally contacted by the support, and caused to follow the support as the counter 100 is disengaged from its drive member.

4. In a calculating machine, the combination with a counter; and a drive member 105 relatively to which the counter is adapted for engagement and disengagement; counter-disengaging means to positively disengage the counter from the drive member and hold it in such disengaged position, said means adapted to be displaced to enable the counter to engage its drive member; means to temporarily retain the counter in its normal disengaged position in an adding operation, upon the displacement of the counter-disengaging means, including 110 a support connected with the counter; and a shiftable step normally contacted by the support, and caused to follow the support as the counter is disengaged from its drive member; means controlled by the counter-disengaging means to unseat the support 115 from the step to effect the engagement of the counter with its drive member, the support as it is unseated, adapted to shift the step to receiving position to accommodate the support when the latter is reseated, as 120 the counter is disengaged from its drive member; and means to reseat the support, during which operation, the support shifts 125

the step back to normal effective position, to take up clearance between the step and the support when the counter is in its normal disengaged position.

5. In a calculating machine, the combination with a drive member adapted to travel back and forth; a counter adapted for engagement and disengagement relatively to the drive member; and counter-disengaging means, to disconnect the counter from its drive member, and hold it disengaged, the counter-disengaging means adapted to be displaced to permit the engagement of the counter with its drive member; of means to retain the counter in its disengaged position, upon the displacement of the counter-disengaging means, in adding operations, until the drive member has completed its travel in one direction, including a support connected with the counter; and a shiftable step on which the support rests upon the displacement of the counter-disengaging means, to hold the counter in normal disengaged position; and means operated by the counter-disengaging means, to trip the support from the step after the drive member has completed its travel in one direction.

6. In a calculating machine, the combination with a drive member; a counter adapted for engagement and disengagement relatively thereto; and counter-disengaging means operable to disengage the counter from its drive member, and to normally hold it disengaged, the counter-disengaging means adapted to be displaced, to permit the engagement of the counter with its drive member, of means to temporarily retain the counter in its normal disengaged position, in adding operations, upon the displacement of the counter-disengaging means, including a support connected with the counter; and a shiftable step on which the support normally rests upon the displacement of the counter-disengaging means; tripping means operated by the counter-disengaging means to unseat the support from the step, to effect the engagement of the counter with its drive member, the support, as it is unseated, adapted to shift the step to position to again accommodate the support when it is reseated as the counter is disengaged from its drive member; and means to reseat the support on the step while the counter is being restored to its normal disengaged position, and to cause the step to follow the support in contact therewith, to its normal position of rest, and take up clearance between the support and the step.

7. In a calculating machine, the combination with a drive member; a counter adapted for engagement and disengagement relatively thereto; and counter-disengaging means operable to disengage the counter from its drive member, and to normally hold it disengaged, the counter-disengaging

means adapted to be displaced, to permit the engagement of the counter with its drive member; of means to temporarily retain the counter in its normal disengaged position in adding operations, upon the displacement of the counter-disengaging means, including a support connected with the counter; and a shiftable step on which the support normally rests upon the displacement of the counter-disengaging means; tripping means operated by the counter-disengaging means to unseat the support from the step, to effect the engagement of the counter with its drive member, the support, as it is unseated, adapted to shift the step to position to again accommodate the support when it is reseated as the counter is disengaged from its drive member; means to yieldingly retain the seat in its receiving position; and means to reseat the support on the step while the counter is being restored to its normal disengaged position, and to cause the step to follow the support in contact therewith, to its normal position of rest, and take up clearance between the support and the step.

8. In a calculating machine, the combination with a drive member; a counter adapted for engagement and disengagement relatively thereto; and counter-disengaging means operable to disengage the counter from its drive member, and to normally hold it disengaged, the counter-disengaging means adapted to be displaced, to permit the engagement of the counter with its drive member; of means to temporarily retain the counter in its normal disengaged position in adding operations, upon the displacement of the counter-disengaging means, including a support connected with the counter; and a shiftable step on which the support normally rests upon the displacement of the counter-disengaging means; tripping means operated by the counter-disengaging means to unseat the support from the step, to effect the engagement of the counter with its drive member, the support, as it is unseated, adapted to shift the step to position to again accommodate the support when it is reseated as the counter is disengaged from its drive member; a stop to arrest the step in receiving position; and means to reseat the support on the step while the counter is being restored to its normal disengaged position, and to cause the step to follow the support in contact therewith, to its normal position of rest, and take up clearance between the support and the step.

9. In a calculating machine, the combination with a drive member; a counter adapted for engagement and disengagement relatively thereto; and counter-disengaging means operable to disengage the counter from its drive member, and to normally hold it disengaged, the counter-disengaging means adapted to be displaced, to permit the en-

gagement of the counter with its drive member; of means to temporarily retain the counter in its normal disengaged position in adding operations, upon the displacement of the counter-disengaging means, including a support connected with the counter; and a shiftable step on which the support normally rests upon the displacement of the counter-disengaging means; tripping means operated by the counter-disengaging means to unseat the support from the step, to effect the engagement of the counter with its drive member, the support, as it is unseated, adapted to shift the step to position to again accommodate the support when it is reseated as the counter is disengaged from its drive member; means to insure the shift of the step to, and to yieldingly retain it in, its receiving position; a stop to arrest the step in receiving position; and means to reseat the support on the step while the counter is being restored to its normal disengaged position, and to cause the step to follow the support in contact therewith, to its normal position of rest, and take up clearance between the support and the step.

10. In a calculating machine, the combination with a drive member; a counter adapted for engagement and disengagement relatively thereto; and counter-disengaging means operable to disengage the counter from its drive member, and to normally hold it disengaged, the counter-disengaging means adapted to be displaced, to permit the engagement of the counter with its drive member; of means to temporarily retain the counter in its normal disengaged position in adding operations, upon the displacement of the counter-disengaging means, including a support connected with the counter; and a shiftable step on which the support normally rests upon the displacement of the counter-disengaging means; tripping means operated by the counter-disengaging means to unseat the support from the step, to effect the engagement of the counter with its drive member, the support, as it is unseated, adapted to shift the step to position to again accommodate the support when it is reseated as the counter is disengaged from its drive member; an adjustment for the step to insure the elimination of lost motion between the support and step when the counter-disengaging means is displaced; and means to reseat the support on the step while the counter is being restored to its normal disengaged position, and to cause the step to follow the support in contact therewith, to its normal position of rest, and take up clearance between the support and the step.

11. In a calculating machine, the combination with a drive member; a counter adapted for engagement and disengagement relatively thereto; and counter-disengag-

ing means operable to disengage the counter from its drive member, and to normally hold it disengaged, the counter-disengaging means adapted to be displaced, to permit the engagement of the counter with its drive member; of means to temporarily retain the counter in its normal disengaged position in adding operations, upon the displacement of the counter-disengaging means, including a support connected with the counter; and a shiftable step on which the support normally rests upon the displacement of the counter-disengaging means; tripping means operated by the counter-disengaging means to unseat the support from the step, to effect the engagement of the counter with its drive member, the support, as it is unseated, adapted to shift the step to position to again accommodate the support when it is reseated as the counter is disengaged from its drive member; an adjustable arm connected to the step; a stop in the path of the arm to hold the step in receiving position; and means to reseat the support on the step while the counter is being restored to its normal disengaged position, and to cause the step to follow the support in contact therewith, to its normal position of rest, and take up clearance between the support and the step.

12. In a calculating machine, the combination with a drive member; a counter adapted for engagement and disengagement relatively thereto; and counter-disengaging means operable to disengage the counter from its drive member, and to normally hold it disengaged, the counter-disengaging means adapted to be displaced, to permit the engagement of the counter with its drive member; of means to temporarily retain the counter in its normal disengaged position in adding operations, upon the displacement of the counter-disengaging means, including a support connected with the counter; and a shiftable step to coöperate with the support, and operable thereby to take up substantially the entire space between the step and the support during the travel of the counter to its normal disengaged position.

13. In a calculating machine, the combination with a drive member; a counter adapted for engagement and disengagement relatively thereto; and counter-disengaging means operable to disengage the counter from its drive member, and to normally hold it disengaged, the counter-disengaging means adapted to be displaced, to permit the engagement of the counter with its drive member; of means to temporarily retain the counter in its normal disengaged position in adding operations, upon the displacement of the counter-disengaging means, including a support connected with the counter; and a tilting step on which the support normally rests, upon the displacement of the counter-

disengaging means; and means controlled by the counter-disengaging means, to trip the support and free the counter for engagement with its drive member.

- 5 14. In a calculating machine, the combination with a drive member; a counter adapted for engagement and disengagement relatively thereto; and counter-disengaging means operable to disengage the counter 10 from its drive member, and to normally hold it disengaged, the counter-disengaging means adapted to be displaced, to permit the engagement of the counter with its drive member; of means to temporarily retain the 15 counter in its normal disengaged position in adding operations, upon the displacement of the counter-disengaging means, including a support connected with the counter; and a tilting step on which the support 20 normally rests upon the displacement of the counter-disengaging means; means controlled by the counter-disengaging means, to trip the support and free the counter for engagement with its drive member; the step 25 adapted to tilt as the support is tripped therefrom; and means to reseat the support as the counter is disengaged from its drive member, the support adapted, by contact with one wall of the step, to turn the step 30 to cause another face to engage and follow the support during the travel of the counter to its normal disengaged position.
15. In a calculating machine, the combination with a drive member; a counter 35 adapted for engagement and disengagement relatively thereto; and counter-disengaging means operable to disengage the counter from its drive member, and to normally hold it disengaged, the counter-disengaging 40 means adapted to be displaced, to permit the engagement of the counter with its drive member; of means to temporarily retain the counter in its normal disengaged position in adding operations, upon the displacement 45 of the counter-disengaging means, including a support connected with the counter; and a shiftable step on which the support is adapted to rest, the step including a rotatable 50 gudgeon, a seat secured thereto, and an adjustable arm connected to the seat; a stop in the path of the arm to arrest the seat in position to accommodate the support upon the disengagement of the counter from its drive member; a spring to yield- 55 ingly retain the seat in receiving position; and a superior spring to reseat the support on the step, and cause the support to turn the step to take up substantially the entire space between the step and support during 60 the travel of the counter to its disengaged position.

16. In a calculating machine, the combination with a series of counters; drive members therefor adapted to travel back and forth; manually set means to control the

extent of travel of the drive members in one direction; counter-disengaging means adapted to disengage the counters from their drive members, and to normally hold the counters disengaged, the counter-disen- 70 gaging means adapted for displacement to enable the engagement of the counters and their drive members; and combined carrying and counter-locking mechanism with which the counters engage when in normal 75 disengaged position relatively to their drive members; of means to temporarily retain the counters in normal disengaged position, in adding operations during the operation of displacing the counter-disengaging means; including a support connected with the counters; and a shiftable step on which the support normally rests, upon the displacement of the counter-disengaging means; the counter-disengaging means adapted to un- 80 seat the support relatively to its step, the support adapted to shift the step to receiving position, as it is unseated; and means to reseat the support on the step during the disengagement of the counters and their 85 drive members, and to cause the support to shift the seat to fit against the support, and follow it until the counters reach their normal disengaged position, relatively to their 90 drive members, and engage the combined 95 carrying and counter-locking mechanism.

17. In a calculating machine, the combination with a combined carrying and counter-locking member having a limited travel in one direction; a drive member; a counter; 100 a pinion fast with the counter and interposed between the counter-locking and drive members, and adapted for engagement and disengagement relatively to each; and counter-disengaging means operable to disen- 105 gage the counter pinion from its drive member and engage it with the counter-locking and carrying member, the counter-disengaging means adapted to be displaced, to permit the disengagement of the counter pinion 110 from its locking member and its engagement with the drive member; of means to retain the counter pinion in its normal disengaged position relatively to its drive member and to insure its proper engagement with the 115 carrying and locking member, including a support connected with the counter; and a shiftable step with which the support normally contacts and operable thereby to take up play and looseness of the connections, 120 during the travel of the counter pinion to its normal engaged position with the carrying and locking member.

18. In a calculating machine, the combination with a combined carrying and coun- 125 ter-locking member having teeth, and adapted for a limited travel in one direction; a toothed drive member; a counter pinion interposed between the two members and adapted for engagement and disengag- 130

ment relatively thereto; and shifting means operable to disengage the pinion from its drive member and engage it with its locking member, the shifting means adapted to be displaced, to permit the disengagement of the pinion from its locking member and its engagement with its drive member; of automatic take-up means to effect the proper mesh of the teeth of the pinion with the teeth of the locking member upon the disengagement of the pinion from its drive member.

19. In a calculating machine, the combination with a combined carrying and counter-locking member having teeth, and adapted for a limited travel in one direction; a toothed drive member; a counter pinion interposed between the two members and adapted for engagement and disengagement relatively thereto; and shifting means operable to disengage the pinion from its drive member and engage it with its locking member, the shifting means adapted to be displaced, to permit the disengagement of the pinion from its locking member and its engagement with its drive member; of automatic take-up means to effect the proper mesh of the teeth of the pinion with the teeth of the locking member upon the disengagement of the pinion from its drive member, including a shiftable step adapted to swing, as the pinion is disengaged from its drive member and engaged with its car-

rying and locking member, to take up looseness and play in the connections.

35

20. In a calculating machine, the combination with a combined carrying and counter-locking member having teeth, and adapted for a limited travel in one direction; a toothed drive member; a counter pinion interposed between the two members and adapted for engagement and disengagement relatively thereto; and shifting means operable to disengage the pinion from its drive member and engage it with its locking member, the shifting means adapted to be displaced, to permit the disengagement of the pinion from its locking member and its engagement with its drive member; of automatic take-up means to effect the proper mesh of the teeth of the pinion with the teeth of the locking member upon the disengagement of the pinion from its drive member, including a shiftable step adapted to swing, as the pinion is disengaged from its drive member and engaged with its carrying and locking member; and step-actuating means connected to travel bodily with the pinions, and adapted to contact the step, to take up looseness and play in the connections.
